CALCULATING MACHINE

Marcus Lothrop, Berkeley, Calif., assignor to
 Friden Calculating Machine Co. Inc., Oakland,
 Calif., a corporation of California

Application May 27, 1935, Serial No. 23,573

7 Claims. (Cl. 235—61)

My invention relates to calculating machines of the power driven type, for performing addition, subtraction, multiplication and division, and is particularly concerned with means for clearing or zeroizing the registers of such machines.

An object of my invention is to provide an improved means for zeroizing or clearing a register in a calculating machine.

The foregoing and other objects are attained in the embodiment of the invention illustrated in the drawing, in which the figure is a diagrammatic view showing schematically a calculating machine constructed in accordance with my invention.

In its preferred form, the calculating machine of my invention includes a register which is altered from zero position by a manually controlled, power-actuated means, the actuation of which preconditions a zeroizing or clear mechanism, preferably power operated, which is then effective upon the manual actuation of another instrumentality to clear or reset the register to zero.

While the calculating machine of my invention is susceptible to a wide range of variations, I have illustrated it herein diagrammatically as being of the "Thomas" type. The structure includes a frame 6 which is stationary and with respect to which a carriage 7 is relatively movable, preferably being laterally translatable with respect to the frame 6. The carriage carries a pair of registers 8 and 9 respectively, in accordance with usual practice. Each of these registers is made up of a plurality of numeral wheels 11 and 12, each bearing suitable indicia 13 and 14. The carriage 7 is translatable by suitable means, such as the hand button 16, and values are introduced into the registers 8 and 9 either directly by an actuator 17 or indirectly thereby through an intermediate mechanism (not shown), dependent upon the number of cycles of operation of the actuator 17. Preferably, the actuator is located on the frame 6 and is driven from a source of power such as an electric motor 18 likewise located on the frame and coupled thereto by suitable gearing 19 and shafting 21. The actuator 17 is simply representative and may include any number of actuating units for any number of different orders in the machine.

Preferably the effect of the actuator 17 upon at least one of the registers 8 and 9 is directly under the control of any selectable one of a plurality or series of manually operable keys 22 arranged in order on the frame 6 and effective

through any standard instrumentality (diagrammatically represented by line 23) to condition the actuator 17 so that a corresponding effect will be had ultimately in one of the registers 8 and 9. Current for the operation of the motor 18 preferably comes from electric mains 24 and 26, respectively, and is carried by a lead 27 to one side of the motor 18 and by a lead 28 through switch contacts 29 and 31, respectively, to the other side of the motor. These contacts 29 and 31 are normally open, but can be resiliently closed to energize the motor 18 by the manual depression of a key 32 with respect to the cover plate 33 on the frame 6. Thus, when the key 32 is depressed it energizes the motor 18 to introduce positive or negative values into the registers 8 and 9. The key 32 can be designated as a motor bar or motor key and represents either a "plus" key, a "minus" key, or any other controlling key customary in calculating machines, which is effective to introduce either positive or negative values into the register.

In order to clear such values from the registers 8 and 9, or, in other words, to return such registers to a zero indication, or to zeroize such registers, each of them is preferably provided with a "clear" bar such as 34 and 36, each of which is translatable under the influence of a thumb button such as 37 or 38, which, when the clear bars are translated thereby, serves to set both registers 8 and 9 to zero, either simultaneously or individually, as the individual clear bars may be operated.

In accordance with my invention, I preferably provide means for zeroizing either or both of these registers, but only after values, either positive or negative, have been introduced into such registers; that is to say, I preferably arrange matters in such a way that operation of a clear key will be ineffective upon the clear or zeroizing mechanism unless such mechanism has been preconditioned by the prior operation of an instrumentality such as the motor key 32.

To this end, the carriage 7 is preferably provided with duplicate clear mechanisms, and since they are identical but one need be described in detail. That is to say, the register 8, for instance, which is cleared by translation of the clear bar 34, has associated with it and located on the carriage 7, a source of power such as the solenoid 39. The solenoid 39 when energized is effective to translate the clear bar 34 against the urgency of a spring 41 and to zeroize the register 8. Upon de-energization of the solenoid 39, the

clear bar is released and, under the influence of the spring 41, returns to its former position, with the register remaining cleared.

In order that the solenoid 39 can be suitably energized, but only after previous operation of the machine, I preferably bring electric current from the main 24 through a changeable resistance 43, which is the only part of the electric circuits which need be varied to suit the current and voltage conditions under which the machine is operated, through a flexible lead 44 which permits current to flow, despite relative movement between the carriage 1 and the frame 6, to the coil of the solenoid 39, from whence the current flows to a contact point 46, to a wire 47, and through another flexible conductor 48, to a lead 49. From this lead a flexible conductor 51 extends to a contact 52 mounted on an insulating base 53 on a key shank 54. This key shank is compressible with respect to the cover plate 33 by actuation of a finger button 56, and is normally maintained in uppermost position by a coil spring 57. As thus far described, the electric circuit is open and stopped at the contact 52, so that depression and release of the key button 56 simply serves to translate the key shank 54 and is ineffective to energize the solenoid 39 to clear the register. The register clear key 56, therefore, is ineffective upon a single manual stroke, but the clear mechanism must be preconditioned to be effective to clear the register. To this end I preferably provide a preconditioning mechanism which is affected by the motor key 32. The motor key carries a pawl plate 58 which is mounted on a pivot 59 fixed on the shank 60 of the key 32, and is normally held against a stop pin 61 by a relatively light spring 62. The pawl plate 58 travels in the same plane as a slide 63 which is constrained to translation on the frame 6 by stationary pins 64 and 66 respectively. A coil spring 67 normally urges the slide 63 into a position in the path of the pawl plate 58.

Upon initial depression of the key 32, the pawl plate 58 yields against the projected slide 63, which is held by its relatively strong spring 67, until key 32 has completed closing the contacts 29 and 31 and pawl plate 58 has moved under slide 63. When the key 32 is manually released, however, and the key shank 60 is returned under the influence of its spring 57 the pawl plate 58 is prevented from yielding in a clockwise direction by the stop pin 61 and translates the slide 63 against the urgency of the spring 67. The slide must be fully translated before the pawl plate 58 can ride out from under the nose of the slide 63 and return to its initial position. This complete translation of slide 63 permits a latch 68 to interengage with a notch 69 in the slide 63. The latch 68 is part of a lever 71 which is pivoted on the frame, as at 72, and is normally urged into latching position by a coil spring 73. Thus, the return of the key 32 after being depressed to energize the motor 18 is effective to cock or latch the slide 63. Any number of subsequent depressions of the key 32 are ineffective upon the slide 63 in its latched position, and the motor 18 can be energized any number of times without out in anywise affecting the slide 63.

When, however, it is desired to operate the clear mechanism which has thus been preconditioned, depression of the key 56 moves the contact 52 toward the slide so that it passes by without touching a contact 75 mounted on an

insulator 76 on the slide 63 and connected by a flexible conductor 77 to a lead 78 joined by a wire 79 to the main 26. That is, if the contact points 52 and 75 were abutted, the circuit would be closed. However, depression of the key 56 does not directly abut the contacts 52 and 75, but the key 56 must be depressed sufficiently far so that the end of its shank 54 contacts a pin 81 at the extremity of the lever 71. The lever is then rotated about its pivot 72 to unlatch the slide 63 which, under the urgency of its spring 67, translates the contact 75 to lie in the path of return of the contact 52. Thus, when the key 56 is released, the superior urgency of the spring 67 lifts the contact 52 to abut the contact 75, which is moved slightly in a direction to recompress the spring 67 and momentarily completes the circuit to the solenoid 39. The key 56 returns to its original position, and the slide 63 likewise returns to its original unlatched position with the contacts 52 and 75 apart. There has thus been a momentary energization of the solenoid 39, to effect a clearing of the register 8.

This momentary closure of the circuit may or may not be sufficient to complete the clearing operation. If it is not sufficient, the momentary energization is utilized to perform a secondary circuit closure in order to maintain the current for an appreciable period. That is to say, when the solenoid 39 is momentarily energized, magnetic attraction is exerted upon an armature 86 mounted upon a spring arm 87 secured to the solenoid and at its extremity carrying a contact 88 which is connected by a wire 89 and a flexible conductor 91 to the wire 79. As soon as the solenoid 39 is energized, therefore, the contacts 46 and 88 are closed and the current is maintained indefinitely. This same energization of the solenoid is also effective to draw the clear bar 34 into the solenoid, and the translation of this bar continues until completion of the clear operation. At the end of the necessary movement, a hammer 92 at the extremity of the bar bends the spring 87 to push the contact 88 away from the contact 46 and to interrupt the circuit. Thus, for clearing the register 8 it is first essential that the motor key 32 be depressed and released in order to precondition the clear mechanism. After the mechanism is once preconditioned it remains in such state until depression of the clear key 56, release of which initiates the clearing operation which proceeds through its cycle to completion and at the end of which time the parts are all restored to their original condition and the register 8 cannot again be cleared until after a subsequent depression and release of the motor key 32.

In order that the register 8 may be cleared, it is provided with a similar solenoid 101, holding contacts 102, flexible conductors 103, and leads 104 and 106, which are connected in the circuit as described in connection with the mechanism for the register 8 and extend to a control key 107 which is preferably located in the frame 63 alongside the key 56 and is connected to identical mechanism. It is usually preferred that the preconditioning of the mechanism for the key 107 be controlled by the motor key 32 which for that purpose is preferably provided with another 70 and duplicate member (not shown) corresponding to the pawl lever 58 but operating in the path of a slide (not shown) appurtenant to the key 107. That is to say, depression and subsequent release of the motor key 32 preferably precon-

ditions both of the mechanisms each associated with the keys 56 and 107, so that either or both of the registers can subsequently be cleared. Thus, while one register can be cleared after an 5 actuation of the motor key 32, the other register can be cleared at any time after the original operation of the motor key 32 and without waiting for a subsequent operation thereof.

Either the key 56 or the key 32 can be depressed at any instant, but they cannot be depressed simultaneously, being prevented by an interlatch in the form of a bar 108 freely slideable on the cover plate 33 which is translated by lugs 109 and 111 upon initial movement of either key 10 to interengage with the shank of the other key to hold it momentarily against inadvertent depression. A centralizing spring 112 restores the bar 108 to neutral position.

The described mechanism is especially applicable to a calculating machine in which the carriage is movable with respect to the frame on which the key instrumentalities are mounted, and in which the source of power, such as the solenoids, is mounted on and movable with the carriage itself, thus facilitating, by means of easily broken electrical connections, the complete removal of the carriage from the frame without the necessity of breaking any difficult mechanical connections. Under no circumstances, furthermore, is it possible to zeroize or clear the 20 register until after either positive or negative values have been introduced therein; or, in other words, it is never possible to clear either or both registers by a single manual stroke, it requiring always a preconditioning stroke and subsequently an energizing stroke.

For a complete disclosure of the type of machine to which my invention is especially applicable, reference is made to the co-pending application of Carl M. Friden, Serial No. 724,482, filed May 8, 1934.

I claim:

1. A calculating machine comprising a register, means for zeroizing said register including a depressible key and normally disabled means settable for control by depression of said key but normally unresponsive to depression thereof, and means including a manually actuated key for enabling said normally disabled means to respond to the control of said depressible key.

2. A calculating machine comprising a register, means for zeroizing said register including a depressible key and normally disabled means controlled by depression of said key, means including a manually actuated key for enabling said normally disabled means, and means controlled

by said normally disabled means for effecting latching thereof in active position.

3. A calculating machine comprising a register, means for zeroizing said register including a depressible key and normally disabled means 5 controlled by depression of said key, means including a manually actuated key for enabling said normally disabled means, means controlled by said normally disabled means for effecting latching thereof in active position, said latching 10 means being related to said depressible key for movement thereby to inactive position.

4. A calculating machine comprising a frame, a register translatable with respect to said frame, key-controlled means on said frame for introducing values into said register, means for zeroizing said register, normally ineffective key-actuated means on said frame for energizing said zeroizing means, and means controlled by said key-controlled means for rendering said key-actuated 20 means effective.

5. A calculating machine comprising a register, means for zeroizing said register, control means for said zeroizing means including a plurality of movable control elements, means responsive to 25 movement of at least two of said control elements for determining operation of said zeroizing means, means for introducing values into said register and moving one of said control elements, and means including a manually actuated key 30 for moving another of said control elements.

6. In a calculating machine, actuating means, a register for operation by said actuating means, power-operated means for zeroizing said register, normally disabled manually operable control 35 means for controlling operation of said zeroizing means, a manually operable control key for said actuating means, and means operable by said key upon operation thereof for enabling said control means to provide for a zeroizing operation in 40 response to manual operation thereof.

7. In a calculating machine, actuating means, a register for operation by said actuating means, power-operated means for zeroizing said register, normally disabled manually operable control 45 means for controlling operation of said zeroizing means, said control means including an element normally in an inactive position and movable therefrom to an active position, whereby manual operation of said control means normally is ineffective, means for initiating a machine operation, and means controlled by said operation initiating means for enabling said control means by moving said element to active position.

MARCUS LOTHROP.
